Primary Examiner — Marissa J Cash*Assistant Examiner* — Altaira J Swangin(74) *Attorney, Agent, or Firm* — Finnegan, Henderson, Farabow, Garrett & Dunner LLP(57) **CLAIM**

The ornamental design for a bed sheet, as shown and described.

DESCRIPTION

FIG. 1 is a top plan view of a bed sheet showing our new design, the bed sheet stretched around a mattress, the mattress forming no part of the claimed design;

FIG. 2 is a bottom plan view thereof;

FIG. 3 is a left side elevation view thereof, the right side view being a mirror image thereto;

FIG. 4 is a front elevation view thereof, the rear elevation view being a mirror image thereto; and,

FIG. 5 is a top plan view of the bed sheet of FIG. 1 shown in an alternate configuration, not stretched around a mattress.

The evenly spaced broken lines shown at the four corners of the bed sheet represent stitching. The dash-dot-dash broken lines represent the boundaries of the claim.
